UNITED STATES PATENT OFFICE.

JOHN C. MUNDAY, OF DAYTON, OHIO, ASSIGNOR, BY MESNE ASSIGNMENTS,
TO NATIONAL CASH REGISTER COMPANY, OF JERSEY CITY, NEW JERSEY.

PRINTING DEVICE FOR CASH-REGISTERS.

SPECIFICATION forming part of Letters Patent No. 683,882, dated October 1, 1901.

Application filed December 17, 1897. Serial No. 662,289. (No model.)

To all whom it may concern:

Be it known that I, JOHN C. MUNDAY, a citizen of the United States, residing at Dayton, in the county of Montgomery and State 5 of Ohio, have invented certain new and useful Improvements in Printing Devices for Cash-Registers; and I do hereby declare the following to be a full, clear, and exact description of the invention.

10 My invention relates to an improvement in check-printing cash-registers or analogous devices. It is especially applicable and I have shown it applied to a cash-register of the type shown in the patent granted to Joseph P. Cleal, June 8, 1897, No. 583,889, or 15 in the patent to Cook, No. 483,511, granted September 27, 1892.

The specific object of my invention is to provide means whereby when an amount is 20 recorded upon the cash-register the coöperating printing devices will print and issue a duplicate check—that is, a check consisting of two parts, on both of which will be printed the amount of the recorded transaction with 25 any other desired data, such as the date and consecutive number, &c.

Referring to the drawings, Figure 1 shows a side elevation of a cash-register of the type referred to with means for printing the duplicate check. Fig. 2 is a perspective view of the printing-cylinder for printing upon the check the date and consecutive number and with the perforating-teeth for indenting the checks, so that the parts may be readily separated. Fig. 3 shows an end view of the printing-cylinder shown in Fig. 2. Fig. 4 shows a view of the front side of the double check, and Fig. 5 shows a view of the rear side of the check.

40 In the several figures of the drawings the same letters of reference indicate identical parts.

The cash-register shown in Fig. 1 of the drawings is of a well-known type, and printing devices of a usual form like that shown in the drawings are in very general use, so that for a specific description of the machine and its parts reference may be had to the before-mentioned patents.

50 In carrying out my invention I employ two

printing-cylinders like that shown in Figs. 2 and 3 of the drawings, which is fully described in the patent to Murphy, No. 541,247, granted June 18, 1895.

Referring to the drawings, the numeral 6 designates the case of the cash-register, which is provided with the usual registering-keys 7. On the left-hand end of the cash-register upon a suitable spindle 8 is the roll of check-paper 9. When the keys are pressed and the driving mechanism of the cash-register actuated, the amount of the transaction is registered and indicated as usual and the revolution-shaft 10 is given one complete turn, carrying with it the usual cam-disk 11, having the internal 65 cam-groove 12. (Shown in broken lines in Fig. 1.) Working in the cam-groove is a stud 13, which is secured to the platen 14, and the cam-groove, it will be noticed, has two printing-points 15 and 16, so that every time the 70 keys are pressed and the driving mechanism actuated the platen will twice raise the check-strip 17 against the type-carriers or printing-segments 18; but the feeding mechanism is so arranged that between the times of printing 75 the two impressions of the type the check-strip is fed on over the platen, so that the amount of the recorded transaction is printed upon the check-strip at two different points every time the cash-register is operated. The knife 19 80 afterward severs the printed check from the check-strip in the usual manner. Rigidly secured to and carried by the cam-disk 11 is a gear 20, shown in broken lines, which meshes with the intermediate gear 21, which in turn 85 engages the gear 22 of the upper printing-cylinder 23, whereby the printing-cylinder is given a complete revolution whenever the cash-register is operated. The feed-roller, (not shown,) upon the left-hand end of which 90 is secured the gear 24, turns with the printing-cylinder 23, and the intermediate gear 25 in turn serves to drive the lower printing-cylinder 26 and the lower feed-roller with which it coöperates and upon the left-hand 95 end of which is secured the gear 27 in the usual manner. The check-strip passing between the lower printing-cylinder 26 and its coöperating feed-roller is thereby fed upward through the chute 28, and while feeding it 100

the lower printing-cylinder prints upon that side of the check-strip which will form the back of the finished check and near the lower end of the latter the date and the consecutive number, as shown in Fig. 5. As the check-strip passes the upper printing-cylinder 23, the latter prints upon the front side thereof and near the upper end thereof the date and the consecutive number, as shown in Fig. 4. As the check-strip passes between the printing-cylinder 23 and its coöperating feed-roller the indenting-teeth 29, which are carried by the upper printing-cylinder 23 and extend along the cylindrical surface thereof, 15 perforate the check, as shown at 30 in Figs. 4 and 5. Thence the check-strip is fed forward over the platen 14, and the printing-point 16 raises the platen and forces the check-strip against the type-segments 18, and 20 thereby the amount of the recorded transaction is printed upon the check above the line of perforation. (See Fig. 4.) The platen then recedes from the printing-type segments 18, and the check-strip is fed forward a short 25 distance, during which time the line of perforation 30 passes the printing-point of the platen, and then the latter is again raised and the check-strip forced against the type-segments, whereby the amount of the recorded 30 transaction is again printed upon the check, but on the opposite side of the line of perforation, and finally the knife 19 severs from the check-strip the printed check in the usual manner.

35 The double check, as shown in Figs. 4 and 5, is useful as a part of a variety of systems for taking care of sales in mercantile houses. In one of the popular systems in connection with which my invention is used when a sale 40 has been made the clerk registers the amount of the transaction upon the register and receives from the latter the double check, which he tears asunder and hands one part to the customer for his purchase and sends the other 45 part to the cashier or proprietor.

Of course my invention is not limited to use in connection with any particular machine, and the check may be used in connection with a variety of systems for handling cash and 50 other transactions.

Having thus described my invention, I

claim as new and desire to secure by Letters Patent—

1. In a cash-register, the combination with a printing device arranged, whenever a transaction is recorded upon the machine, to print characters representing the amount of the said transaction a plurality of times at different points on the check-strip during a single operation of the machine and means for perforating said check-strip at a point between the duplicate characters so that it may be afterward torn apart. 55

2. In a cash-register, the combination with type-carriers arranged to print duplicate impressions at different points upon a check-strip during a single actuation of the driving mechanism of the register and means for perforating a printed check transversely between the respective duplicate impressions. 60

3. In a machine of the class described the combination with type-carriers, of feed-rollers arranged to feed a check-strip to the type-carriers, rotary means for perforating or indenting a check-strip, means for causing the type-carriers to print characters representing the amount of the recorded transaction a plurality of times at different points on a check-strip, and a knife for severing the printed end of a check-strip. 70

4. In a cash-register, the combination with a printing mechanism arranged to print upon a paper check or strip duplicate impressions of the amounts recorded, of a perforating device arranged to perforate said strip at a point between the duplicate impressions, and a knife for severing the checks from said strip. 85

5. In a cash-register, the combination with a printing mechanism arranged to print upon a paper check or strip duplicate impressions of the amounts recorded during a single operation of the machine, means for feeding a strip forward at a period between the two impressions, and means for perforating a check-strip between the duplicate impressions. 90

In testimony whereof I affix my signature in presence of two witnesses.

JOHN C. MUNDAY.
